TYPOGRAPHICAL DISTRIBUTING
MECHANISM

William B. Abbott, Springfield Gardens, and Paul Hilpman, Garden City, N. Y., assignors to Mergenthaler Linotype Company, a corporation of New York

Application February 1, 1951, Serial No. 208,970

14 Claims. (Cl. 199—43)

1

This invention relates to typographical distributing machines, such as Linotype machines of the general organization represented in U. S. Letters Patent to O. Mergenthaler, No. 436,532, wherein circulating matrices are released from a magazine in the order in which they are to appear in print and then assembled in line, the composed line transferred to the face of a mold, the mold filled with molten metal to form a type bar or slug, and the matrices thereafter returned through a distributing mechanism to the magazine from which they started.

In being distributed, the matrices are individually fed to a horizontal distributor bar, conveyed therealong by a set of rotating screws driven through a clutch arrangement from the intermediate drive shaft of the machine, and, finally, released at different points along the bar for return to appropriate channels in the magazine. During the operation of the distributing mechanism, it sometimes happens that the rotation of the screws is abnormally resisted because of faulty distribution caused, for example, by a jammed matrix. In such cases, it is the function of the distributor clutch to break the driving connection between the intermediate shaft and the distributor screws in order to prevent damage to the parts.

The distributor clutch arrangement generally employed comprises driving and driven members held in frictional engagement by a spring through a mechanical connection, which includes pairs of oppositely disposed beveled surfaces ordinarily positioned for engagement with each other. When undue resistance to motion is offered to the driven member, the beveled surfaces are forced out of engagement and allow the spring to interrupt the frictional engagement between the clutch members.

While this clutch arrangement has performed satisfactorily for years on standard commercial Linotype machines, nevertheless it has failed to meet the high standards of sensitivity required for high speed machines, such as are shown and described in the application for U. S. Letters Patent of Louis Rossetto, et. al., Serial No. 184,072, filed September 9, 1950.

The present invention provides an improved clutch device of greatly increased sensitivity and one in which a force of approximately 1½ lbs. acting upon the distributor screws is sufficient to produce disengagement of the driving and driven members, whereas formerly a force of the order of 6 to 8 lbs. was required. In addition, after their disengagement, provision is made for

2

automatically locking the driven member out of operative relationship with the driving member until manually released and reset.

These and other improvements will be more fully pointed out in the detailed description to follow.

Referring to the drawings:

Fig. 1 is a front elevation of the improved distributor clutch arrangement as applied to a Linotype machine;

Fig. 2 is a sectional view taken along the line 2—2 of Fig. 1;

Fig. 3 is a sectional view taken along the line 3—3 of Fig. 1;

Fig. 4 is a side view, partly diagrammatic, of the upper part of the machine illustrating one of the safety features of the present invention; and

Fig. 5 is a detail view, partly in section, showing how one of the driven parts is keyed to its shaft.

During distribution, the matrices are conveyed along the distributor bar (not shown) by a pair of upper rotating screws 1 and a single lower rotating screw 1^a until they arrive at their points of release and then permitted to fall by gravity through a short magazine entrance 2 into the appropriate channels of the particular matrix storage magazine 3 which happens to be in use.

The screws 1 and 1^a are supported at opposite ends in bearings A, which are themselves mounted upon the horizontal crosspiece of the distributor frame B comprising arms B¹ rising from the main base frame of the machine. The upper screws 1 have little or no end play, but the lower screw 1^a, although normally banking against the right bearing A (as viewed in Fig. 1) is permitted some slight axial movement in a leftward direction.

40 The distributor screws are constantly driven through a clutch from the intermediate drive shaft (not shown), which latter serves to drive a pulley 4 by means of a belt 5. The pulley 4 is loosely mounted on a horizontal shaft 6 between a pair of collars 7 to prevent end play; and a driven disk 8, the facing 9 of which is adapted under normal circumstances to bear against the side of the drive pulley 4 to maintain frictional engagement therewith, is attached to a threaded sleeve 10 slidably disposed by means of a keyway on the shaft 6. The driving connection to the upper screws 1 is completed through a gear 11 mounted on the shaft 6 and a gear arrangement denoted generally by the reference character 12 in Fig. 1 and, in the case of the

lower screw 1^a , through a gear 13 mounted at the right hand extremity of its supporting shaft which extends beyond the bearing A (see Fig. 3).

The horizontal shaft 6 is supported from a casting C of the distributor frame B and rotatably mounted in a bearing 14 thereof. As best shown in Figs. 2 and 5, the sleeve 10 is provided with a key 15 arranged for longitudinal displacement in an elongated slot formed in the shaft 6 (Fig. 5) to permit the movement of the driven disk 8 into and out of engagement with the drive pulley 4 . The shaft 6 is hollowed out at its right end to house a tension spring 17 and a plunger 18 which, acting against the key, normally serve to maintain the necessary frictional engagement between the disk and pulley. The right end of the shaft 6 extends beyond the bearing 14 and is externally threaded to permit the attachment of a knurled knob 16 as well as internally threaded to house an adjustable screw 19 which regulates the pressure exerted by the spring.

As explained above, to prevent damage to the matrices or to the machine parts when one or more matrices becomes lodged in the distributor screws, the lower screw 1^a is permitted to float or yield axially in its bearings in a leftward direction as a result of the camming action which will always occur between the rotating screw threads and the jammed matrix or matrices, and this axial movement of the lower screw 1^a is utilized in the present invention to effect the disengagement of the clutch.

Toward this end, a pair of cooperating inverted U-shaped members 20 and 25 (Figs. 1 and 3) sensitively serve to transmit the slightest leftward movement of the lower screw 1^a to the clutch disengaging mechanism. The member 20 , having connected arms 20^a and 20^b , is pivotally suspended from the distributor frame B by means of a short fore-and-aft shaft 21 , whereas the member 25 , having arms 25^a and 25^b , is pivotally mounted to the front of the casting C by means of a short horizontal shaft 26 (Fig. 1). The arm 20^a carries at its lower end a roller 22 which acts against the left face of the gear 13 (Fig. 1), under tension of a light spring 24 , and thus serves to maintain the lower screw 1^a in its normal rightward position. The other arm 20^b carries a plate 23 having a vertical knife edge 23^a (see Fig. 3) and a downwardly projections portion 23^b (Fig. 1). The knife edge 23^a normally engages the back edge of a plate 25^c , which latter is attached to the aforesaid arm 25^a of the member 25 . The arm 25^b carries a small roller disk 27 at its lower end; and a compression spring 28 , acting on the member 25 above the pivot shaft 26 , maintains the disk 27 in constant readiness for engagement with the threaded sleeve 10 . This tendency, however, is normally resisted by the knife edge 23^a or until the knife edge is pivoted out of the path of the plate 25^c by the axial displacement of the screw 1^a , at which time the disk 27 is permitted to engage one of the threads of the rotating sleeve 10 , camming the latter in a rightward direction along the shaft 6 and thereby disengaging the driven disk 8 (which, as has been explained, is attached to the threaded sleeve) from frictional engagement with the face of the drive pulley 4 .

Once the clutch has been disengaged as the result of an abnormal condition in the distributor, provision is made for locking the clutch out of operation until it is manually reset for further operation. Toward this end, an adjustable slide 29 is mounted in the casting C (Figs. 2 and 3)

and carries at its rear side a small pair of rollers 29^a . The threaded sleeve 10 is provided at its right end with a thin collar 31 which, during the rotation of the shaft 6 , is free to rotate between the small rollers 29^a but which serves to shift the slide 29 to the right when the sleeve 10 is so displaced during disengagement. As best shown in Figs. 1 and 2, the slide 29 is positioned in the casting C by means of a vertical pin 30 extending through an elongated hole or slot 29^b (Fig. 2) of the slide, the purpose of said slot being to allow sufficient endwise movement of the slide during the disengagement of the clutch. The slide is accurately prepositioned with respect to the collar 31 by means of a built-in compression spring 29^c and a set screw 29^d , the former normally serving to maintain the slide in a leftward position as determined by the setting of the screw, but capable of compression during disengagement when the slide 29 is shifted rightwardly by the collar 31 , as just described.

A spring-urged locking pawl 32 is pivotally mounted at the front of the casting C and, during the normal operation of the distributor, is held out of active position by the depending finger 33 on the arm 25^b . It is clear, however, that when the disk 27 is permitted to engage the threaded sleeve 10 and displace it, as well as the collar 31 and the slide 29 , in a rightward direction to disengage the clutch, the finger 33 by its inward movement will permit the spring-urged locking pawl 32 to move across the left end of the slide 29 (Figs. 2 and 3), thereby securely holding the driven disk 8 away from the drive pulley 4 against the pressure of the spring 17 .

Summarizing the operation of the improved clutch device, the driving mechanism for the distributor screws includes the driving pulley 4 , the disk 8 frictionally driven by the pulley, the horizontal shaft 6 to which the driven disk 8 is keyed, and an arrangement of gears connecting the screws to the shaft. The frictional engagement between the driving and driven members is normally maintained by the compression spring 17 .

The lower screw 1^a , although normally positioned to the right by the action of the spring 24 and the roller 22 , is capable of leftward axial displacement when one or more matrices become lodged in the distributor, and the slightest such displacement swings the knife edge 23^a out of the path of the plate 25^c , permitting the roller disk 27 to engage the rotating threaded sleeve 10 and thereby cam the driven disk 8 out of engagement with the driving member 4 . The rightward movement of the sleeve 10 also shifts the slide 29 to the right, permitting the spring operated pawl 32 , which has previously been released by the movement of the disk 27 into engagement with the sleeve 10 , to lock the slide 29 (and hence also the driven disk 8) out of operative position.

After having been disengaged, the clutch device can be quickly and conveniently reset in a single operation, once the troublesome condition has been eliminated. For this purpose, the plate 25^c is provided with an outstanding portion having a notch 25^d therein including a beveled edge 25^e (Fig. 3) which latter, when moved forwardly, bears against the aforementioned projection 23^b (Fig. 1) and pivots the member 25 in a counter-clockwise direction, as viewed in Fig. 1, resetting the screw 1^a in its normal rightward position through the medium of the roller 22 and the knife edge 23^a in the path of the plate 25^c . The U-shaped member 20 is provided with an upwardly standing handle portion 20^f , which can be easily

pressed inwardly against the counterforce exerted by the spring 28 in order to facilitate this resetting operation. As shown in Fig. 3, the casting C is provided with a similar upstanding portion C¹ to limit the swing of the member 25 during resetting so that the projection 23^b always remains positioned within (i. e. will not be cammed out of) the notch 25^d.

In the commercial machine of the class described, the magazine entrance 2 is mounted on a pair of arms 35 (Fig. 4) pivotally attached to the arms B¹ of the distributor frame and may be swung backwardly to permit access to the interior parts. Obviously, if distribution of matrices were attempted while the magazine entrance is out of operative position, the matrices would not find their way back to their proper magazine channels but, in fact, would be scattered about the top of the machine, falling as they may. To prevent this occurrence and as an added safety feature, the present invention provides for the automatic disengagement of the clutch device whenever the magazine entrance is out of proper position. Thus, a lever 36 is pivotally mounted on the bearing A at the right side of the machine and is provided with an upstanding beveled finger 37 (see Figs. 3 and 4), arranged for engagement with the head of a set screw 38 carried by the aforementioned arm 29^a of the member 29. The finger 37 is normally urged rearwardly (i. e. in a clockwise direction as viewed in Fig. 4) by the action of a compression spring 39 against said lever 36, causing the beveled portion of the finger, through its engagement with the set screw 38, to cam the member 29 in a leftward direction (as viewed in Fig. 1) and thereby, as we have already seen, to effect the disengagement of the clutch. The right magazine entrance supporting arm 35, however, carries a set screw 40 which, when the magazine entrance 2 is in operative position, acts against the lever 36 to overcome the force exerted by the spring 39 and, consequently, positions the beveled finger 37 out of contact with the set screw 38.

In conclusion, it should be understood that, although the present invention has been shown and described in a single specific form and by way of example, many variations and modifications may be made therein which will still be comprised within its spirit. It is to be understood, therefore, that the invention is not limited to any specific form or embodiment, except insofar as such limitations are specified in the appended claims.

What is claimed is:

1. Typographical distributing mechanism comprising, in combination, rotatable screws for conveying matrices along a distributor bar, one of said screws being displaceable axially driving and driven members normally frictionally engaged to transmit power to the screws, a driven shaft, a threaded sleeve fast to the driven member and keyed to said shaft, a spring-urged locking pawl to hold the driven member out of operative relationship with the driving member but normally held out of operation, and means controlled by the axial displacement of said distributor screw and presenting an element engageable with the threads of said threaded sleeve for shifting the driven member out of operative relationship with the driving member and releasing said locking pawl.

2. A combination according to claim 1, including a single hand operated lever for resetting the displaced distributor screw and the locking

pawl and reconditioning the clutch for further operation.

3. Typographical distributing mechanism comprising, in combination, rotatable screws for conveying matrices along a distributor bar, driving means, a driven shaft mechanically connected to the screws, a driven member mounted on said shaft and normally frictionally engaged with the driving means, a threaded member fast to said driven member and common to said shaft, a pivoted arm normally suspended out of operative engagement with the threads of said threaded member, means controlled by one of the screws for releasing said arm into engagement with the threads of said threaded member, said arm by such engagement being operative to shift the driven member out of engagement with the driving means, and a hand operated lever for resetting the screw controlled means and the pivoted arm to recondition the clutch for further operation.

4. A combination according to claim 3, including means for positively locking the driven member out of operative relationship with the driving means until released by said hand operated lever.

5. In a typographical distributing mechanism wherein the power for driving the distributor screws is transmitted thereto through a friction clutch arrangement and wherein one of said screws is displaceable axially, the combination of a driven shaft, a threaded sleeve slidably mounted thereon and associated with the frictionally driven member of the clutch, a pivoted arm adapted for engagement with the threads of said threaded sleeve to effect the disengagement of the clutch, a knife edge normally serving to hold the arm out of engagement with the threads of said threaded sleeve, means controlled by the axial displacement of said distributor screw for removing the knife edge to effect the disengagement of the clutch, and hand operated means for resetting the pivoted arm and knife edge to recondition the clutch and to reestablish the driving connection to the screws.

6. Typographical distributing mechanism comprising, in combination, rotatable screws for conveying matrices along a distributor bar, one of said screws being axially displaceable under abnormal conditions, power means for rotating the screws including a clutch, a trip device actuated by the axial movement of the distributor screw, and means controlled by said trip device for opening the clutch, said clutch opening means including an axially movable threaded sleeve attached to one of the clutch members, and a roller disk movable into engagement with the threads of said threaded sleeve upon actuation of the trip device, said roller disk by such engagement causing the sleeve to move axially and open the clutch.

7. A combination according to claim 6, wherein the roller disk is carried by a pivoted arm which normally holds the disk out of engagement with the threads of the threaded sleeve and which is maintained in such normal position by the trip device.

8. Typographical distributing mechanism comprising, in combination, rotatable screws for conveying matrices along a distributor bar, one of said screws being axially displaceable under abnormal conditions, power means for rotating the screws including a clutch, a trip device actuated by the axial movement of the distributor screw, means controlled by said trip device for opening the clutch, and automatic means distinct from

said clutch opening means for positively locking the clutch in its open position.

9. A combination according to claim 8, wherein the automatic locking means comprise a spring-urged locking pawl which is normally held out of action when the clutch is closed but which is thrown into action by the movement of the clutch to open position.

10. A combination according to claim 8, including manually operable means to disengage the locking means when desired and permit the closing of the clutch.

11. A combination according to claim 8, wherein the automatic locking means comprise a spring-urged locking pawl, and a cooperating slide coupled to and movable with the movable clutch member, said slide in the closed position of the clutch holding the pawl out of action and in the open position of the clutch releasing the pawl for action.

12. Typographical distributing mechanism comprising, in combination, rotatable screws for conveying matrices along a distributor bar, one of said screws being displaceable axially under abnormal conditions, power means for rotating the screws including a clutch, a threaded sleeve fast to the movable clutch member, a spring actuated pivoted arm having an element for engagement with the threads of said sleeve to effect the disengagement of the clutch, a second spring actuated pivoted arm having a knife edge engagement with the first pivoted arm to hold the latter normally out of operation but sensitive to

5 the axial displacement of the distributor screw to release said first pivoted arm for operation, hand operated means for resetting the first pivoted arm and its knife edge engagement with the second pivoted arm to permit the closing of the clutch, and connections between the two arms whereby the resetting of the first arm will effect the resetting of the second arm and through the latter the resetting of the displaced distributor screw.

10 13. A combination according to claim 12, including a spring actuated pawl for positively locking the clutch in its open position, said pawl being normally held out of action by the first pivoted arm but thrown into action by its spring when said arm is released for operation.

15 14. A combination according to claim 13, including connections between the first pivoted arm and the locking pawl whereby the latter is restored to its normal inactive position against the opposition of its spring by the resetting of said arm.
